CLAIM

The ornamental design for a cutting insert with flower-shaped seating area, as shown and described.

DESCRIPTION

FIG. 1 is an isometric view of a cutting insert with flower-shaped seating area showing our new design;

FIG. 2 is a top view of the cutting insert with flower-shaped seating area of FIG. 1, the bottom view being identical to the top view; and,

FIG. 3 is a side view of the cutting insert with flower-shaped seating area of FIG. 1, each side view being identical to each other.

1 Claim, 2 Drawing Sheets

FIG. 1

FIG. 2

FIG. 3
